UNITED STATES PATENT OFFICE.

HARRISON E. KLEFFEL, OF NEW YORK, N. Y.

APPARATUS FOR DELIVERING AIR TANGENTIALLY TO AN AIR REGISTER.

Application filed September 24, 1923. Serial No. 664,516.

To all whom it may concern:

Be it known that I, HARRISON E. KLEFFEL, a citizen of the United States, residing on Manhattan Island, in the city, county, and State of New York, have invented certain new and useful Improvements in Apparatus for Delivering Air Tangentially to an Air Register; and I do hereby declare the following to be a full, clear, and exact description 10 of the invention, such as will enable others skilled in the art to which it appertains to make and use the same.

The invention relates to air control registers for fuel burners, and has for its 15 object to provide a scientifically proportioned scroll casing surrounding an air control register that will convert the pressure difference existing between the furnace and the draft pressure into the highest velocity 20 so that the maximum quantity of air can enter the register uniformly with equal distribution.

A further object is to provide a register casing that will deliver air uniformly to 25 the register with less drop in draft pressure, and greater discharging capacity.

A further object is to provide a casing to fit on any standard air control register and provide an inlet duct that may point in any 30 direction.

The foregoing and other features of my invention will now be described in connection with the accompanying drawing forming part of this specification, in which I 35 have represented my air register in its preferred form, after which I shall point out more particularly in the claims those features which I believe to be new and of my own invention.

In the drawings:

Figure 1 is a diagrammatic sectional view of my register and casing.

Figure 2 is a front view thereof.

In the carrying out of my invention the 45 refractory wall 1 of any suitable furnace is provided with an opening 2, standard air register 3, atomizer 4. The register 3 is provided with means 5 shown as shutters or doors, to regulate the air entering the furnace, all of which is common to fuel burners and requires no further detailed description herein.

Surrounding the air register 3 I provide 50 a casing 6 shaped like a volute scroll not unlike the casing used in hydraulic turbines of the volute type and provided with a

tangential inlet 7. This is mounted to a plate 8 in the furnace front and adapted to be rotated about the axis of the burner and held in any position. To effect this, the 60 plate 8 may have a flange 8' provided with a grooved edge, in which groove the edge of the casing 6 fits. The friction between the two parts is normally sufficient to hold the casing in any adjusted position. 65

By referring specifically to Figure 2 it will be readily understood that as the air enters the inlet 7, the shape of the volute air passage changes the draft pressure into increasing velocity, thereby equalizing the 70 amount of air entering the air register between the regulating means 5.

The volute chamber 6 gradually contracts as the air moves into the register which maintains the velocity of air. 75

I wish it distinctly understood that my apparatus herein described and illustrated is in the form in which I desire to construct it and that changes or variations may be made as may be convenient or desirable without departing from the salient features of my invention and I therefore intend the following claims to cover such modifications as naturally fall within the lines of invention. 80

I claim:

1. An air register, a casing surrounding the same and provided with a tangential air inlet and means for mounting said casing to permit the air inlet to be pointed in any direction in one plane. 90

2. An air register, a casing surrounding the same and provided with a tangential air inlet, and a mounting for said casing which permits its rotation to point the air inlet in any direction in the plane of rotation. 95

3. An air register, a casing surrounding the same and provided with an air inlet, the space between the casing and the register constantly decreasing as the distance from the inlet increases. 100

4. An air register, a casing surrounding the same and provided with an inlet passage, the space between the casing and the register being in the form of a single volute scroll. 105

5. An air register fitting in an opening in a furnace front and adapted to regulate the amount of air passing to the furnace and a casing surrounding the register and provided with an air inlet, the air passage between the casing and register having the form of a single volute scroll. 110

6. An air register, a casing surrounding

the same and provided with an air inlet, the space between the casing and the register decreasing as the distance from the inlet increases, and means for mounting the casing to permit the air inlet to be pointed in varying directions.

7. An air register, a casing surrounding the same and provided with a tangential air inlet, the space between the casing and the register being in the form of a volute scroll, and means for mounting the casing to permit it to be moved to point the air inlet in all directions in one plane.

8. An air register, a casing surrounding the same and having a tangential air inlet, means for regulating the amount of air passing through the register, the passage between the casing and the register being in

the form of a volute scroll, and means for mounting the casing to permit its rotation 20 to point the air inlet in any direction in the plane of rotation.

9. An air register fitting in an opening in a furnace front, and a casing surrounding the air register and provided with a single 25 tangential inlet, said casing being formed to deliver air tangentially in substantially uniform amounts to all portions of the air register.

In testimony whereof I affix my signature 30 in the presence of two witnesses.

HARRISON E. KLEFFEL.
